WIRE FACED ROLL FOR PAPERMAKING MACHINES

Harry G. Specht, Montclair, N. J., assignor to
Encor Corporation, Belleville, N. J., a corpora-
tion of New Jersey

Application April 17, 1939, Serial No. 268,166

10 Claims. (Cl. 92—43)

The present invention relates to an improvement in wire faced rolls for papermaking machines, and particularly dandy rolls and cylinder moulds, an object of the invention being to provide a roll structure which may be manufactured economically, and will be extremely rigid and light in weight, while at the same time providing maximum drainage and freedom from clogging.

Heretofore the usual practice in manufacturing dandy rolls and cylinder moulds has been to first construct a rigid frame composed of rods either wound or supported lengthwise in relation to spiders, these rods being soldered at all crossing points so as to provide a rigid support. Upon this support a wire is wound helically to provide a foundation support for the fine wire mesh covering, which is placed about the roll and sewed or otherwise fastened at the seam. This construction has the disadvantage that it requires a great amount of skilled manual labor, making its manufacture both slow and expensive, it is extremely difficult to obtain uniformity, each roll being practically custom built, and the construction necessitated considerable weight of metal per square inch of surface in order to obtain the required rigidity and strength. Also the contacting relation between the wire mesh covering and the wound wire supporting structure prevented maximum drainage and caused fibres to become clogged therein.

It is proposed in the present invention to provide a roll in which the supporting frame consists of a series of sheet metal units so constructed and arranged as to provide a rigid cylindrical structure, having projecting fins for supporting the wire mesh covering with a minimum of contact between such fins and the covering, so that there will be no appreciable obstruction to the mesh openings, and to provide drainage openings of relatively large extent spaced inwardly from the wire mesh covering. It is proposed to give such structural shape to the sheet metal channel units and the fins that they will be extremely rigid and at the same time will provide funnel-like guide surfaces for the unobstructed passage of the drainage of water therethrough. It is further proposed to provide a structure which will enable rolls of any desired lengths and diameters to be produced, and in which a perfect cylindrical surface concentric to the axis of the roll may be obtained with facility.

With the above and other objects in view, an embodiment of the invention is shown in the accompanying drawing, and this embodiment will

be hereinafter more fully described with reference thereto, and the invention will be finally pointed out in the claims.

In the drawing:

- 5 Fig. 1 is a side elevation of a dandy roll, the intermediate portion being broken away, and a portion of the wire mesh covering being broken away to show the supporting structure.
- Fig. 2 is an end view thereof.
- 10 Fig. 3 is a perspective view showing a portion of one of the frame producing channel units from one end.
- Fig. 4 is a perspective view showing the same from the other end.
- 15 Fig. 5 is a fragmentary plan view on an enlarged scale as compared to Figs. 1 and 2, showing a portion of the supporting frame structure, with the wire mesh covering partially broken away.
- 20 Fig. 6 is a view partially in end elevation and partially in transverse section, taken along the line 6—6 of Fig. 5.
- Fig. 7 is a transverse sectional view taken along the line 7—7 of Fig. 5.
- 25 Fig. 8 is a longitudinal sectional view, taken along the line 8—8 of Fig. 5.
- Similar reference characters indicate corresponding parts throughout the several figures of the drawing.
- 30 Referring to the drawing, the dandy roll, or cylinder mould according to the exemplary illustrated embodiment of the invention, comprises a supporting shaft 10 on which there is supported a series of circular spider heads 11, 35 suitably spaced apart to provide the necessary support for the cylindrical wire mesh supporting structure, as will hereinafter more fully appear. In the case of the usual dandy roll the diameter may be approximately one to two feet and the length as much as 16 or 20 feet, depending upon the width of the Fourdrinier machine upon which the roll is used. The spider heads in this case will preferably be spaced apart approximately one foot. In Fig. 1 the two end spider heads are shown and the spider head adjacent one end, the intermediate portion of the roll being broken away. In the case of the cylinder mould the diameter is substantially greater than that of the dandy roll, while the length is shorter.

40 While the shaft 10 is shown as extending entirely through the roll it will be understood that it is only necessary to the structure to employ short end shafts secured to the end spider heads, 45 in which case the intermediate spider heads will

not be shaft-supported, but will simply be held in place by their connection with the cylindrical supporting structure, as will presently more fully appear.

Each of the spider heads 11 is provided in its outer periphery with a series of spaced radial slots 12 in which are secured the flanges of the cylindrical supporting structure, as will presently more fully appear.

The cylindrical supporting structure is made up of a series of strip members, each extending the length of the roll. These strip members are formed from a strip of relatively thin sheet metal, preferably bronze or brass, but which may be of any suitable material, this strip being bent into channel form to provide side flanges 13 and 14 and a transverse connecting portion 15, and from which portion 15 a series of longitudinally spaced transversely disposed fins 16 is bent upwardly, these fins being lanced from the transverse portion 15 to provide a series of longitudinally spaced substantially rectangular openings 17, there being an opening adjacent each fin.

Each fin is bent upwardly at right angles and a sufficient portion of the transverse portion 15 remains to provide a support for the fin. In order to render the fin rigid against bending, and also to impart to its outer edge a transversely widened supporting surface, it has a rib 18 pressed therein, which is substantially semi-circular in outline, and this rib is continued into the portion 15 at a downwardly inclined angle, as at 19, the portions of the transverse connecting portion 15 at each side of the portion 19 being depressed as at 20-20. This renders the fin and its supporting portion 15 rigid against bending, and at the same time provides a surface which is free of any corners or flat surfaces in which paper fibers may become lodged, the surface acting as a deflecting funnel-like guide for draining the water which passes through the mesh covering of the roll through the openings 17. The flanges 13 and 14 converge slightly toward their lower edges, so that in the assembled relation in the roll they are substantially radial with respect to the axis of the roll.

In assembling the support-forming members the flange 13 of one strip is placed in contact with the flange 14 of the adjacent strip, and these two flanges are inserted into one of the slots 12 of the spider heads. The strips are preferably so arranged that the fins of one strip will be offset with respect to the fins of the adjacent strip, as shown clearly in Fig. 5, thus providing a uniformly distributed supporting surface for the wire mesh covering.

Instead of the arrangement, where all of the strips are similarly placed, as shown in Fig. 5, alternate strips may be placed in reverse arrangement, so that the ribs 18 of the alternate strips will project in opposite direction from the ribs 18 of the other strips.

The contacting flanges 13 and 14 of the adjacent strips are secured together by brazing, or they may be secured by coating them with solder and then sweating them together, and the flange ends inserted in the slots 12 are rigidly secured to the spider heads by brazing or soldering these inserted portions in the slots. After assembly of the support-forming strips in the roll, and before mounting of the wire mesh covering, the roll is preferably placed in a lathe or grinding machine, and the outer surface is machined or ground to a true cylinder with respect to the axis. Thus any irregularities that may occur in

the projection of the fins will not impair the production of a perfect cylindrical supporting surface.

The fine mesh wire covering 21 is placed over the cylindrical supporting roll in contact with the outer supporting edges of the fins 16, and is sewed, soldered, or otherwise suitably secured at the seam 22 to complete the finished roll. In order to prevent any shifting or creeping of the wire mesh covering its end edges are secured at the underside by spots of solder 23 connecting it at suitably spaced points to certain of the end fins 16, as shown in Fig. 8.

Inasmuch as the channel strips forming the supporting structure may be of a very thin gauge light metal, while still providing a rigid support for the wire covering, the edge surfaces of the fins in contact with the wire mesh can approximate the diameter of the wires from which the wire mesh is woven, so that there will be no appreciable obstruction to the mesh openings. At the same time the relatively large openings 17, which are spaced inwardly from the wire mesh covering, provide clear passage for the drainage of water therethrough without any chance of clogging, the inclined surfaces of the portions 15 being self-cleaning as water passes over them. In the event of damage to a roll, it is a simple matter to repair it by removing and replacing the damaged part, and thereupon refinishing the surface of the whole roll to provide a perfect cylindrical support.

I have illustrated and described a preferred and satisfactory embodiment of the invention, but it will be understood that changes may be made therein, within the spirit and scope thereof, as defined in the appended claims.

Having thus described my invention, what I claim and desire to secure by Letters Patent is:

1. In a cylinder roll for papermaking machines, a cylindrical supporting structure for a wire mesh covering comprising a plurality of longitudinally spaced coaxial circular head members, a plurality of circumferentially arranged supporting members extending between said head members and connected thereto, said supporting members having longitudinally spaced openings and longitudinally spaced fins projecting outwardly and each having a longitudinally extending reinforcing means inwardly spaced from the outer edges of said fins, the outer edges of said fins constituting a supporting surface for the wire mesh covering outwardly spaced from said longitudinally extending reinforcing means.
2. In a cylinder roll for papermaking machines, a cylindrical supporting structure for a wire mesh covering comprising a plurality of longitudinally spaced coaxial circular head members, a plurality of circumferentially arranged supporting members arranged parallel to the axis of said head members extending between said members and connected thereto, said supporting members having longitudinally spaced openings and longitudinally spaced fins projecting outwardly and each having a longitudinally extending reinforcing flange inwardly spaced from the outer edges of said fins and radially disposed with respect to the axis of said head members, the outer edges of said fins constituting a supporting surface for the wire mesh covering outwardly spaced from said longitudinally extending reinforcing flanges.
3. In a cylinder roll for papermaking machines, a cylindrical supporting structure for a wire mesh covering comprising a plurality of

longitudinally spaced coaxial circular head members, a plurality of circumferentially arranged supporting channel strip members arranged parallel to the axis of said head members extending between said members and connected thereto, the transverse portions of said strip members having longitudinally spaced openings and longitudinally spaced fins projecting outwardly, the outer edges of said fins constituting a supporting surface for the wire mesh covering the flanges of said channel strip members projecting inwardly and constituting longitudinal supports for a wire mesh covering inwardly spaced from the outer edges of said fins.

4. In a cylinder roll for papermaking machines, a cylindrical supporting structure for a wire mesh covering comprising a plurality of longitudinally spaced coaxial circular head members, a plurality of circumferentially arranged supporting channel strip members arranged parallel to the axis of said head members extending between said members and connected thereto, the transverse portions of said strip members having longitudinally spaced openings and longitudinally spaced fins projecting outwardly, the outer edges of said fins constituting a supporting surface for the wire mesh covering, the side flanges of said strips projecting inwardly and contacting the flanges of adjacent strip members and constituting double thickness longitudinal supports for said wire mesh covering inwardly spaced from the outer edges of said fins.

5. The invention as defined in claim 4, further characterized by metallic adhesion joints rigidly connecting said contacting flanges.

6. The invention as defined in claim 4, further characterized by metallic adhesion joints rigidly connecting said strip members to said head members.

7. The invention as defined in claim 4, further characterized in that said head members are provided in their peripheries with radially disposed spaced slots engaged by said contacting flanges of said strip members.

8. In a cylinder roll for papermaking machines, a cylindrical supporting structure for a wire mesh covering comprising a plurality of longitudinally spaced coaxial circular head members, a plurality of circumferentially arranged supporting members extending between said head

members and connected thereto, said supporting members having longitudinally spaced openings, there being a transverse supporting portion adjacent one edge of each of said openings, and a fin projecting outwardly from said supporting portion at an angle thereto, the outer edges of said fins constituting a supporting surface for the wire mesh covering each of said fins being substantially perpendicularly arranged and its transverse supporting portion being at an obtuse angle thereto to deflect water from the surface of said fin toward the edge of said supporting portion.

9. In a cylinder roll for papermaking machines, a cylindrical supporting structure for a wire mesh covering comprising a plurality of longitudinally spaced coaxial circular head members, a plurality of circumferentially arranged supporting members extending between said head members and connected thereto, said supporting members having longitudinally spaced openings, there being a transverse supporting portion adjacent one edge of each of said openings, and a fin projecting outwardly from said supporting portion at an angle thereto, a reinforcing rib in said fin extending into said reinforcing portion to render it resistant to bending and to deflect water from the surface of said fins toward the edge of said supporting portion, the outer edges of said fins constituting a supporting surface for the wire mesh covering.

10. In a cylinder roll for papermaking machines, a cylindrical supporting structure for a wire mesh covering comprising a plurality of longitudinally spaced coaxial circular head members, a plurality of circumferentially arranged supporting members extending between said head members and connected thereto, said supporting members having longitudinally spaced openings, there being a transverse supporting portion adjacent one edge of each of said openings, and a fin projecting outwardly from said supporting portion at an angle thereto, a reinforcing rib in said fin extending to the outer edge of said fin to provide a transversely widened supporting edge portion, the outer edges of said fins constituting a supporting surface for the wire mesh covering.

HARRY G. SPECHT.
